(57) **CLAIM**

The ornamental design for a control unit, as shown and described.

DESCRIPTION

FIG. 1 is a front perspective view of a control unit showing our new design.

FIG. 2 is a front view of the control unit of FIG. 1.

FIG. 3 is a rear view of the control unit of FIG. 1.

FIG. 4 is a left side view of the control unit of FIG. 1.

FIG. 5 is a right side view of the control unit of FIG. 1.

FIG. 6 is a top view of the control unit of FIG. 1; and,

FIG. 7 is a bottom view of the control unit of FIG. 1.

The broken lines illustrate portions of the control unit which form no part of the claimed design.

1 Claim, 6 Drawing Sheets(56)
